UNITED STATES PATENT OFFICE.

CHARLES H. VIOL, OF PITTSBURGH, PENNSYLVANIA, ASSIGNOR TO STANDARD CHEMICAL COMPANY, OF PITTSBURGH, PENNSYLVANIA.

RADON TUBE OR IMPLANT.

Application filed April 23, 1924. Serial No. 708,512.

To all whom it may concern:

Be it known that I, CHARLES H. VIOL, a citizen of the United States, and resident of Pittsburgh, in the county of Allegheny and 5 State of Pennsylvania, have invented certain new and useful Improvements in Radon Tubes or Implants; and I do hereby declare the following to be a full, clear, and exact description of the invention, such as will 10 enable others skilled in the art to which it appertains to make and use the same.

This invention relates to improvements in containers for radon or radium emanation, such as employed for inserting radon into 15 affected tissues.

In the therapeutic application of radon (radium emanation), this gaseous radioactive decay product of radium is separated from a radium solution in which it has accumulated, purified and then sealed in varying amounts in small glass tubes.

A most useful method of employing radon tubes consists in the making of very tiny glass tubes, for example about 3 mm. long 25 and 0.3 mm. in diameter, each containing in the order of a millicurie of radon, and then embedding these tiny tubes to form implants within the mass of tumor tissues. The implantation is done by placing the radon tube 30 in the tip of a suitable hollow needle provided with a stylet. After placing the radon tube in the top of the needle, with the stylet somewhat withdrawn to make room therefor, the needle is plunged to the desired 35 point in the tumor mass, then very slightly withdrawn, and the radon tube is forced out into the tissue by pushing on the stylet. On withdrawing the hollow needle, the radon tube remains embedded as an implant 40 in the tumor mass.

It has been found to be difficult to pick up and manipulate the tiny glass radon

tubes as usually made of colorless transparent glass and it is the object of this invention to provide radon tubes or implants 45 which may be readily visible and hence facilitate the handling and manipulation of the same.

With the above mentioned object in view, the invention consists in a radon tube or implant having such intense color appearance 50 as to render the same readily visible to facilitate the handling or manipulation of the same.

The accompanying drawing illustrates 55 radon tubes or implants embodying my invention and being shown on a greatly exaggerated scale.

Instead of making these minute tubes or implants of clear glass as has heretofore 60 been the custom, I propose to make them of glass having an intense color appearance, the material giving the color being embodied, preferably, in the glass, although the color effect might in some cases be produced 65 by an insoluble coating on the tube or implant.

The tube or implant may be made to have a black appearance as indicated at 1, or a deep blue appearance as indicated at 2, or 70 a purple appearance as indicated at 3, but in any case the appearance of the tube or implant should be intense in color.

Having fully described my invention what I claim as new and desire to secure 75 by Letters Patent, is:

A radon tube or implant having such intense color appearance as to render the same readily visible to facilitate the handling or manipulation of the same.

In testimony whereof, I have signed this specification.

CHARLES H. VIOL.
